WINDOW VENT

Raymond A. McCarroll, 1725 Newcastle, Grosse Pointe Woods, Mich. 48236

Filed Mar. 24, 1972, Ser. No. 238,000

Term of patent 14 years

Int. Cl. D12—16
U.S. Cl. D12—181

FIG. 1 is a perspective view of a window vent showing my new design, it being understood that the broken lines are for illustrative purposes only;

FIG. 2 is a side elevational view thereof;

FIG. 3 is a greatly enlarged fragmentary sectional view taken on the lines 3—3 of FIG. 2;

FIG. 4 is an enlarged fragmentary sectional view taken on the lines 4—4 of FIG. 2, it being understood that the broken lines are for illustrative purposes only.

FIG. 5 is an enlarged sectional view taken on the lines 5—5 of FIG. 2;

FIG. 6 is a greatly enlarged fragmentary front elevational view taken on the lines 6—6 of FIG. 2 and looking in the direction of the arrows;

FIG. 7 is a greatly enlarged fragmentary front elevational view taken on the lines 7—7 of FIG. 2 and looking in the direction of the arrows.

I claim:

The ornamental design for a window vent, as shown and described.
